UNITED STATES PATENT OFFICE.

HENRY SUMNER KEMP, OF RICHMOND, VIRGINIA, ASSIGNOR, BY DIRECT AND MESNE ASSIGNMENTS, TO THE REVERSIBLE ELECTRIC CAR SIGN CO., OF RICHMOND, VIRGINIA, A CORPORATION OF VIRGINIA.

PORTABLE ELECTRICALLY-ILLUMINATED SIGN.

SPECIFICATION forming part of Letters Patent No. 711,867, dated October 21, 1902.

Application filed February 25, 1902. Serial No. 95,599. (No model.)

To all whom it may concern:

Be it known that I, HENRY SUMNER KEMP, a citizen of the United States, residing at Richmond, in the county of Henrico and State of 5 Virginia, have invented new and useful Improvements in Portable Electrically-Illuminated Signs, of which the following is a specification.

This invention relates to certain new and 10 useful improvements in portable electrical illuminated signs particularly adapted for use in connection with electrically-propelled vehicles for indicating the route of the same, although the sign is applicable for advertising 15 and other purposes.

The object of the invention is to construct an electrical illuminated sign which can be detached from and connected to the vehicle at any point desired, closing when connected 20 to the vehicle an electrical circuit for the purpose of illuminating the sign.

The invention further aims to provide an electrical illuminated sign with a new and novel contact-supporting hanger, which in 25 conjunction with suitable supports and contact-forming devices carried by the vehicle or other support enables the sign to be positioned and supported at any point desired.

The invention further aims to construct an 30 electrical illuminated sign which shall be extremely simple in its construction, strong, durable, and comparatively inexpensive to set up; and to this end it consists of the novel combination and arrangement of parts hereinafter more specifically described, illustrated 35 in the accompanying drawings, and particularly pointed out in the claims hereunto appended.

In describing the invention in detail reference is had to the accompanying drawings, 40 wherein the improved electrical illuminated sign is shown as connected to a street-railway car, and in which—

Figure 1 is an elevation, broken away, of 45 the dashboard of a car, showing the support and contact-forming device secured thereto. Fig. 2 is a vertical sectional view of the sign attached to the dashboard of the car. Fig. 3 is a top plan view thereof, partly broken 50 away. Fig. 4 is a rear elevation of the sign

with the contact-forming device and support therefor in section, and Fig. 5 is a bottom plan of the contact-forming device.

Referring to the drawings by reference-numerals, wherein like numerals of reference 55 indicate corresponding parts throughout the several views, 1 denotes the dashboard of an electrically-propelled street-railway car, although the invention is applicable to other vehicles which are electrically propelled or 60 vehicles wherein a storage battery can be employed for illuminating the sign; but for the purpose of fully illustrating the invention I have shown the adaptation of the device to the dashboard of an electrically-propelled 65 street-railway car, although the sign may be attached to other parts of the car instead of the dashboard, if desired. To the dashboard, as shown, is secured the contact-forming device, which consists of a hollow casing 2, 70 having an open bottom and one of its side walls provided with a slot 3. The rear wall of the casing 2 is formed with the apertured extensions 4, through which extend the fastening means 4' for securing the contact device in position. Within the casing 2 is arranged a pair of insulated blocks 5, which abut against the inner face of the rear, front, and slotted side wall thereof. The blocks 5 are of a width corresponding to the distance 80 between one end of the slot and the corresponding end of the slotted side wall, or, in other words, the blocks 5 are of such size that they do not pass the edges of the slot 3. Arranged within the casing 2 and abutting 85 against the inner face of the side wall opposite the slot 3 is a pair of insulated plates 6 7, which also abut against each other and are secured in position by means of the bolt 8, which extends through them and said side 90 wall and which carries on its outer end the fastening-nut 9. The plate 6 carries the binding-screw 10 for the positive conductor or wire 11, the latter passing through a part of the said plate 6. The screw 10 also secures to 95 the plate 6 the laterally-extending contact-spring 12, which projects between the blocks 5 near one side thereof, or, in other words, the binding-screw 10 is adapted to electrically connect one end of the conductor 11 with 100

the contact-spring 12. The plate 6 also carries the binding-screw 13 for the negative conductor or wire 14, which passes through the plate 7, thence up through the plate 6, where 5 it engages with the screw 13. The latter also secures to the plate 6 the laterally-extending contact-spring 15, which projects between the blocks 5 near one edge thereof—that is to say, the springs 12 and 13 extend between the 10 blocks 5 a suitable distance apart. The screw 13 is adapted to electrically connect together the spring 15 and the conductor or wire 14. The rear wall of the casing 2 is formed with a suitable opening, through which extend the 15 conducting-wires 11 14, adapted to be in communication with a source of electrical supply.

The reference-numeral 16 denotes a latch pivoted at one end to the slotted wall of the casing 2 and is adapted to have its free end 20 engage in a keeper 17, secured to the slotted side wall at a point opposite the pivotal connection of the latch. The function of the latch will be hereinafter set forth.

Arranged below the contact-forming device 25 is a supporting-bracket consisting of a vertical and horizontal member 18 and 19, respectively, the latter formed integral approximately centrally with the outer face of the former and provided with a cupped end 20, 30 having an opening 21. The function of the cupped end 20 will be hereinafter described. The vertical member 18 is formed with suitable openings, through which extend the fastening means 21 for securing the supporting-bracket 35 in position, as shown, to the dashboard 1 below the contact device. The horizontal member 19 is provided with a hinged plate for closing the cupped end thereof when the supporting-bracket is not in use. This 40 plate is adapted to prevent the entrance of any foreign matter to the cupped end, and the opening in the cupped end is adapted to permit the discharge of any matter if it should enter the said cupped end.

45 The sign consists of a frame 22, carrying the removable face or sign plate 28, the latter having the names of the street, stations, advertising inscriptions, or other matter thereon. The inscription upon the plate 23 is formed of 50 transparent material constituting the sign or indicator, which when illuminated plainly presents said names or other matters or when used in connection with the car, so that the route of the car may be readily read off. The 55 frame 22 is preferably constructed of a single piece of sheet metal and substantially concavo-convex in contour, although any configuration may be employed; but the frame should be provided with rear, top, and bottom walls 60 24 25 26, respectively. The inner face of the frame 22 is coated with white enamel, porcelain, or other suitable means, forming thereby a deflector. The front edge of the frame is constructed with an inwardly-extending 65 flange 27 for retaining the plate 23 in position. The frame is also provided in one side with an opening 28 to permit of the entrance of

the plate 23. The frame is provided in its top with a handle 29. One side of the frame 23 has connected thereto a vertically-extending 70 loop 30, which when the plate is in position is adapted to align with a similar loop 31, carried by the frame.

The reference-numeral 32 denotes a fastening-pin constructed with a pair of arms, which 75 engage in the loops 30 31 for retaining the plate 23 to the frame 22 to prevent the removal of the former unless the fastening-pin is disconnected from the loops 30 31. The top and bottom walls have each secured to their inner 80 face the guide-strips 33 34 for the plate 23. To the rear face of the wall 25 of the frame 22 is secured, by means of the straps 35 36, a vertical member 37, forming a hanger, which may be constructed of any suitable material, 85 rectangular in cross-section of suitable length, and is provided with a vertical passage 39, extending centrally thereof from near the top to near the bottom and then at right angles to the remaining portion, as at 40. Extending through the passage 39 are the leading-in wires 41 42 for the lamp 43, mounted upon the base 44, carried by the bottom wall 26 of the frame. The rear wall 25 of the frame is provided with an opening which registers with 90 the right-angled portion 40 of the passage 39 to permit of the entrance of the leading-in wires 41 42. The top of the passage 39 communicates with an opening 45, which is closed at each side by means of the contact-plates 95 46 47, respectively. These communicate with their respective leading-in wires and are adapted to contact with the springs 12 15. 22' is a door to permit of access to the frame.

The sign is set up in the following manner: 105 The plate 23 is secured in the frame 1 by means of the fastening-pin and is carried to the vehicle or car, and the lower portion of the vertical member or hanger 37 inserted in the cup-shaped end of the supporting-bracket and the upper end inserted in the contact-forming device through the slotted side wall thereof, so that the contact-plates of the vertical member engage with the contact-springs 12 and 15, as shown in Fig. 2 of 110 115 the drawings. When the sign is in this position, the latch 16 engages in the keeper 17 and secures the upper end of the vertical member 37 in position—that is to say, prevents the vertical member from becoming dislodged from the contact-forming device. It will be obvious that the horizontal member 19 with its cupped end will support the sign, owing to the position of the lower end of the vertical member or hanger 37 therein. When 120 125 it is desired to remove the sign, all that is necessary is to open the latch, grasp the handle of the frame, slide the vertical member or hanger from between the contact-springs 12 15, and then remove the vertical member 130 or hanger from the cup-shaped end of the horizontal member 19 of the supporting-bracket.

It is thought the many advantages of a

portable electrical illuminated sign constructed in the manner set forth can be readily understood from the foregoing description, taken in connection with the accompanying drawings, and it will also be noted that various minor changes may be made in the details of construction without departing from the general spirit of my invention.

In some cases the sign proper may be dispensed with and the article used simply as a headlight or other device, the term "illuminated sign" being simply employed as a convenient one and as descriptive of the specific embodiment of the invention shown in this application.

Having thus fully described my invention, what I claim as new, and desire to secure by Letters Patent, is—

1. In a portable electrical illuminated sign, the combination with a suitable frame provided with a lamp and carrying a face or sign plate, of a hanger secured to said frame, leading-in wires extending through said hanger and connected to said lamp, contact-plates attached to said hanger and engaging said wires, a contact-forming device in communication with a source of electrical supply, adapted to receive the upper end of said hanger and engage with said contacts for closing an electrical circuit, a supporting-bracket provided with a cupped end to receive the lower end of said hanger for securing the sign in position, and means for retaining the upper end of said hanger within the contact-forming device.

2. In a portable electrical illuminated sign, the combination with a suitable frame provided with a lamp and carrying a face or sign plate, of a hanger secured to said frame and provided with a suitable passage terminating at its top in an opening, a contact-plate for closing each end of said opening, electrical conductors extending through said passage and connected at their upper end to said plates and at their lower end to said lamp, a contact-forming device in communication with a source of electrical supply and adapted to engage with the said plates for closing an electrical circuit thereby illuminating said lamp, and a supporting-bracket adapted to receive the lower end of said hanger for retaining the sign in position.

3. In an electrical illuminated sign, a hanger therefor consisting of a vertical member provided with a passage, conductors extending through the passage and contact-plates connected to the vertical member and engaging with the conductors, a contact-forming device communicating with a source of electricity and engaging with the contact-plates for closing an electrical circuit, means for retaining the vertical member within said contact-forming device, and a supporting-bracket adapted to receive the vertical member for retaining the sign in position.

4. In an electrical illuminated sign, a contact-forming device consisting of a hollow

casing having an open bottom and one of its side walls slotted and a pair of contact-springs secured therein and in communication with a source of electrical supply, a supporting-bracket provided with a cupped end, a hanger for the sign, contact-plates carried by the hanger and suitably connected to a translating device, said hanger adapted to be inserted in said casing through the slotted side wall thereof so that the contact-plates will engage with the said contact-springs for closing an electrical circuit, said hanger adapted to be inserted in the cupped end of said bracket for retaining the sign in position, and means connected to the contact-forming device for securing the hanger therein.

5. In an electrical illuminated sign, a contact-forming device consisting of a hollow casing having an open bottom and a slotted side wall, a pair of insulated plates secured within the casing and a pair of contact-springs connected to said plates and in communication with a source of electrical supply, a hanger for the sign, contact-plates carried by the hanger and suitably connected to a translating device, said hanger adapted to be inserted in said casing through the slotted side wall thereof so that the contact-plates will engage with the said contact-springs for closing an electrical circuit, and a supporting-bracket for said hanger.

6. In an electrical illuminated sign, a contact-forming device consisting of a hollow casing, a pair of insulated plates secured therein and a pair of contact-springs connected to said plates and in communication with a source of electrical supply, a hanger for the sign, contact-plates carried by the hanger and suitably connected to a translating device, said hanger adapted to be inserted in said casing so that the contact-plates will engage said springs for closing an electrical circuit, and a bracket provided with a cupped end adapted to receive said hanger for supporting the sign.

7. In an electrical illuminated sign, a contact-forming device consisting of a hollow casing, a pair of insulated plates secured therein and a pair of contact-springs connected to said plates and in communication with a source of electrical supply, a hanger for the sign, contact-plates carried by the hanger and suitably connected to a translating device, said hanger adapted to be inserted in said casing so that the contact-plates will engage said springs for closing an electrical circuit, a bracket provided with a cupped end adapted to receive the said hanger for supporting the sign, and means connected to the casing for retaining the hanger therein.

8. In an electrical illuminated sign, a contact-forming device consisting of a hollow casing, a pair of insulated plates secured therein and a pair of contact-springs connected to said plates and in communication with a source of electrical supply, a hanger for the

- sign, contact-plates carried by the hanger and suitably connected to a translating device, said hanger adapted to be inserted in said casing so that the contact-plates will engage said springs for closing an electrical circuit, and a bracket consisting of a vertical and a horizontal member, the latter provided with a cupped end adapted to receive the hanger for supporting the sign.
- 10 9. In an electrical illuminated sign, a contact-forming device consisting of a hollow casing, a pair of insulated plates secured therein and a pair of contact-springs connected to said plates and in communication with a 15 source of electrical supply, a hanger for the sign, contact-plates carried by the hanger and

suitably connected to a translating device, said hanger adapted to be inserted in said casing so that the contact-plates will engage said springs for closing an electrical circuit, 20 a bracket consisting of a vertical and a horizontal member, the latter provided with a cupped end adapted to receive the hanger for supporting the sign, and a latch connected to the casing for retaining the hanger therein. 25

In testimony whereof I have hereunto set my hand in presence of two subscribing witnesses.

HENRY SUMNER KEMP.
